UNITED STATES PATENT OFFICE.

ALBERT NEAL, OF KOKOMO, INDIANA.

LIFTING-JACK.

1,384,539.

Specification of Letters Patent. Patented July 12, 1921.

Application filed January 28, 1921. Serial No. 440,777.

To all whom it may concern:

Be it known that I, ALBERT NEAL, a citizen of the United States, residing at Kokomo, in the county of Howard, and State of Indiana, have invented certain new and useful Improvements in Lifting-Jacks, of which the following is a specification.

This invention relates to a lifting jack and embodies certain improvements and advantages over those shown and described in my prior patents, for instance, No. 1,355,842 and No. 1,355,843, wherein the lifting bar can be raised and lowered in progressive order, and also including means whereby the load can be dropped at one operation if desired.

One of the objects of the present invention consists in the provision of means whereby in dropping the load at a single operation I am still able to regulate and control the speed of descent of the lifting bar and its load, and which is an important feature especially if the load comprises an article of delicate or expensive construction.

There are other objects which will appear from a perusal of the following description and claims, and which I accomplish by means of the construction illustrated in the accompanying drawings, forming a part hereof, in which—

Figure 1 is a vertical sectional view through the frame of the jack, in which the movable parts are shown in elevation, on the plane 1—1 in Fig. 3. Fig. 2 is a rear elevation of the lifting jack. Fig. 3 is a front elevation of the lifting jack on the plane 3—3 in Fig. 1. Fig. 4 is a fragmentary detail view in the same plane as Fig. 1, showing the pawls at the limit of their range of travel in elevating the lifting bar. Fig. 5 is a view similar to Fig. 4, except that the actuator lever is shown as depressed to the limit of its travel so as to disengage both of the pawls from the lifting bar. Fig. 6 is a transverse sectional view on the plane 6—6 in Fig. 4. Fig. 7 is a fragmentary detail view in side elevation of the lifting jack frame. Fig. 8 is a view showing the lifting jack partly in horizontal section and partly in top plan. Fig. 9 is a perspective view of one of the lifting pawls.

Referring to drawings, 15 represents the lifting jack frame which is provided with a longitudinal slot 16 which forms one of the assisting means for guiding the lifting bar in a determined path of travel, and the two parts of the frame thus divided by slot 16

are connected at the bottom by a base member 17 and at the top by a cross rib 17' to form a substantially rigid frame structure. As shown in Fig. 6 slot 16 is off-set or widened within the frame of the jack to provide a pair of opposed ribs 18, and, as will hereinafter appear, these ribs prevent the outward displacement of the lifting bar from the frame of the jack. The width of slot 16 is also reduced at one point by means of the projections 19 on the faces of the opposed ribs 18 (Fig. 2), and the lifting bar 20 is provided with the extensions or protuberances 21 which will pass the projections 19 only after applying considerable pressure to the lifting bar, so that after the parts are in an assembled condition their accidental separation is prevented. The inner side walls of the lifting jack frame are also provided with fixed cam-shaped surfaces 22 (Figs. 5 and 3), which perform certain functions to be hereinafter more particularly described.

As shown in Fig. 6, lifting bar 20 is T-shaped in cross section in which the cross-bar of the T projects and slides behind the shoulders formed by the opposed ribs 18, and the stem of the T slides in slot 16 of the frame of the jack. The front face of lifting bar 20 is provided with a series of teeth 25 by means of which longitudinal movement may be imparted to said bar, and the bar 20 is further provided with a longitudinally disposed groove 26 which is V-shaped in cross section (Fig. 6), and the object of this groove will be hereinafter described.

The frame of the jack is provided with a pair of lateral extensions 30, and these extensions are provided with a pair of slots 31 which are enlarged at their lower closed ends to form pockets to receive the trunnions 32 on the head 33 of the actuator lever 34. Trunnions 32 are formed to correspond to the diameter of the enlarged pockets of slots 31, but one side of each trunnion is dressed away to so reduce its diameter and permit it to pass through the slots 31 if held in proper relation with the slots. After the trunnion 32 enters the enlarged end of the slot it may then be given a slight turn so as to present its increased diameter to the slot and thus prevent the accidental separation of the actuator lever 34 from the jack frame.

As before stated, trunnions 32 are carried by head 33 which forms a part of the actuator lever 34. As shown in Fig. 5, the up-

per and central portion of head 33 is channeled to provide a flange 35 at each side of the head, and arranged between and supported by the flanges 35 are the movable 5 pawls 38 and 39 which engage the teeth 25 and impart longitudinal movement to the lifting bar 20. Pawls 38 and 39 are also removably mounted in the flanges 35. This I accomplish by providing one or 10 both of the flanges 35 with the slots 40 which terminate at their lower ends in enlarged pockets to receive the trunnions 41 of the pawls. When the flanges 35 are each provided with the slots 40 each 15 trunnion 41 has its diameter reduced in one direction so as to admit its ready introduction to the slots 40, after which the pawls are shifted sidewise so as to remove the reduced diameter and present their increased 20 diametrical portions to the slots. However I prefer to provide one of the flanges 35 with apertures and the remaining flange with the slots 40, so that by reducing the diameter of the trunnions on one side of the 25 pawls, and adjacent to the bodies of the pawls, will permit the reduced portions of the trunnions to pass through the slots 40, and after they enter the enlarged portions of the slots the pawls may then be moved 30 sidewise so as to cause the opposite trunnion ends to enter the apertures in the opposite flange 35 and at the same time present the full diametrical portions of the reduced trunnions to the slots 40. When the pawls 35 are placed in operative position in head 33 and the latter is inserted into the jack frame, the pawls are prevented from moving sidewise and becoming displaced from their 35 bearings by means of the inner faces of the 40 lateral extensions 30.

The construction and assembling of the parts so far described discloses that when the pawls 38 and 39 are arranged in operative position in head 33 and the latter is inserted into operative position in the jack frame the displacement of all of these parts is prevented, and the parts can not be taken apart until they are turned into determined 45 positions to permit their removal and disassembly. It may also be stated that the pawls 38 and 39 are pivotally mounted in head 33 and are arranged relatively to the axes of the trunnions 32 so that a prescribed movement is imparted to the pawls 50 at each movement of the actuator lever 34, but this range of movement of the pawls is reduced sufficiently after inserting the lifting bar 20 into the jack frame to prevent the removal of the lever 34 and the trunnions 32 from the bearing slots 31 until the 55 removal of the lifting bar is first effected from the jack frame. Hence, the lifting bar 20 becomes a key for maintaining all of the parts of the jack in assembled operative 60 position, and, as heretofore pointed out, con-

siderable force being necessary to remove the lifting bar 20 from the jack frame, it necessarily follows that all of the parts of the jack are maintained in operative position, and that their assemblment and disassembly can only be effected by first removing bar 20 and then passing the several parts through the various movements in proper sequence.

As heretofore stated, the pawls 38 and 39 are pivotally mounted in head 33 and relatively to the axes of trunnions 32 to normally cause the pawls to alternately move in opposite directions when the actuator lever 34 is oscillated. Hence, when the actuator lever 34 is moved from its normal position shown in Fig. 1 to its higher position shown in Fig. 4 the upper pawl 39 elevates the lifting bar 20 a distance equaling the height of one of the teeth 25. While pawl 39 is thus undergoing movement in elevating lifting bar 20 and its load the lower pawl 38 moves downwardly and is disengaged from the teeth 25 by means of the underside and marginal edges of the pawl coming into contact with the cam-shaped surfaces 22 heretofore referred to as being fixed on the inner side walls of the jack frame. Pawl 38 is thus held out of contact of teeth 25 until pawl 39 reaches the limit of its upward travel, and when the movement of the actuator lever 34 is reversed and the pawl 39 starts to withdraw from the teeth 25 the lower pawl 38 moves forward and its free end enters the space between the teeth in front of the cam surfaces 22 before the pawl 38 is completely disengaged from teeth 25. During the continued downward movement of actuator lever 34 from its position shown in Fig. 4 to that shown in Fig. 1, lower pawl 38 merely supports the load without imparting any longitudinal movement to the lifting bar 20 while the upper pawl 39 is moving downwardly to effect a new point of contact in the lower portion of the lifting bar 20. When it is desired to drop the load the actuator lever 34 is depressed from its normal position shown in Fig. 1 to that shown in Fig. 5, and the extent of this added downward movement of the lever so increases the range of movement of head 33 about its axis as to effect the disengagement of both pawls from the teeth 25 and allowing the lifting bar and the load to descend. As shown in the drawings, the actuator lever 34 is rather short which enables the jack to be easily packed in a tool box or chest, and to provide the desired leverage in lifting loads up to the normal capacity of the jack I provide a detachable handle 42 which may readily be attached and detached from the actuator lever 34. The end of handle 42 adjacent the frame of the jack is provided with a lateral foot extension 43 which comes into contact with the outer faces of the 130

extensions 30 of jack frame 15 and acts as a stop for limiting the normal downward travel of the actuator lever 34 and handle 42. When the foot extension 43 comes into contact with extensions 30 the impact is felt by the operator so that during the operation of elevating the load he will apply no additional pressure to cause further depression of the handle 42 but will reverse the movement of the handle, for the reason that a further depression of the handle 42 below its normal position indicated in Fig. 1 will cause both of the pawls 38 and 39 to be disengaged from the teeth in the lifting bar 20, leaving the latter unsupported and free to drop. If the load is in an elevated position and the operator desires to drop it he depresses lever 34 after the foot 43 contacts the extensions 30, the additional pressure to cause handle 42 to move below its normal position is sufficient to force the handle 42 to move longitudinally and independently on actuator lever 34 a sufficient distance to afford the necessary clearance and freedom of the additional movement of head 33 about its axis to cause both of the pawls 38 and 39 to be disengaged from the lifting bar 20, all as clearly indicated in Fig. 5.

In my former patents heretofore referred to, I was able to drop the load by depressing the actuator handle beyond its normal range of travel, thereby withdrawing both of the pawls simultaneously and leaving the lifting bar free to move downwardly. In these former devices I was unable to control or regulate the speed of descent of the lifting bar and its load, and it is one of the primary objects of this invention to provide means that after I have disengaged and set free the lifting bar, to continue to regulate and control the downward travel of said bar and the load sustained thereon, which is of considerable importance if the thing lowered is of delicate and expensive construction. This I accomplish by means of a longitudinal groove or channel 26 in the lifting bar and which is shown as V-shaped in cross section in Fig. 6. The head 33 of the actuator lever 34 is provided with an integral cam-shaped rib 50 which registers with and in cross section corresponds to the shape of channel 26. During the normal operation of the actuator lever 34, that is to say, from the position shown in Fig. 1 to that shown in Fig. 4, the cam 50 imposes no restraining effect upon the free longitudinal movement of the lifting bar 20, and it is only when the actuator lever is depressed below its normal range of travel as shown in Fig. 5 that its movement simultaneously disengages both of the pawls 38 and 39 from the lifting bar and renders cam 50 effective, for the reason that the actuator lever has moved through a sufficient arc of travel about its pivot to move the

cam 50 into the V-shaped groove 26. The degree of restraint that the cam 50 imposes on the movement of the lifting bar is determined largely by the operator, depending upon the speed attained by the lifting bar under a given weight and the amount of pressure exerted by the operator on the actuator lever. In other words, the breaking effect of the cam 50 is determined by the pressure applied to the actuator lever 34 by the operator.

From the foregoing description it will be observed that when my improved lifting jack is employed as an automobile jack, and the motor vehicle is elevated to change a tire, I can impose a restraint when lowering the vehicle and thereby prevent possible injury thereto. The present jack is intended to be manufactured in various sizes, and can be made in convenient form for use by section men on railways. When a jack is designed for the latter use, the transverse foot 43 on the end of the handle 42 becomes quite an important feature. As shown in Figs. 1 and 3 the free end of this latter extension 55 is provided in its edge with a recess or notch 55 which may be readily utilized both as a crow bar and as a means for withdrawing the spikes from the cross ties.

Having thus fully described my said invention, what I desire to secure by Letters Patent, is—

1. A lifting jack comprising a frame, a movable tooth lifting bar guided in said frame, an actuator lever oscillatively supported in said frame, a pair of pawls pivotally supported in the end of the actuator lever and adapted to alternately engage the lifting bar when the lever is oscillated, said lever capable of being depressed a sufficient distance to disengage both pawls for releasing and freeing the lifting bars, and means carried by the actuator lever for imparting a frictional contact for controlling the downward movement of said bar.

2. A lifting jack comprising a frame provided with a longitudinal slot, a movable T-shaped lifting bar guided in said frame with the stem of the T riding in said slot, extensions on the side walls of the slot and similar extensions on the side walls of the lifting bar, the two extensions operating to prevent accidental displacement of the lifting bar from said frame, a pair of pawls pivotally mounted in the end of the actuator lever to alternately engage the lifting bar when the actuator lever is oscillated, said lever being susceptible of being depressed a distance to disengage both of the pawls and releasing the lifting bar, and means for controlling the downward movement of said released bar.

3. A lifting jack comprising a frame having a pair of aligned slots terminating in enlarged pockets, a movable lifting bar guided

within said frame, an actuator lever oscillatively supported in said frame, trunnions on the lever having their diameter reduced in one direction for passage through the slots in the frame, a detachable handle for increasing the leverage of the actuator lever and also indicating the normal downward travel of said lever, the detachable handle being susceptible of independent longitudinal movement on the lever to afford additional travel for the actuator lever and pawls.

4. In a lifting jack, a frame, a movable lifting bar guided in said frame said bar being provided with a longitudinal channel

having inwardly converged sides, an actuator lever removably mounted in said frame, a pair of pawls removably mounted in said actuator for successively elevating the bar when said lever is oscillated, and means carried by the lever for frictionally engaging the side walls of the channel when both pawls are disengaged from the bar.

In witness whereof, I have hereunto set my hand and seal at Indianapolis, Indiana, this 17th day of January, A. D., one thousand nine hundred and twenty one.

ALBERT NEAL. [I. S.]
